UNITED STATES PATENT OFFICE.

ALFRED CZARNIKOW, OF BERLIN, GERMANY, ASSIGNOR TO ARTHUR CZARNIKOW, OF BERLIN, GERMANY.

SPRING-ACTUATED MOTOR.

1,096,829.

Specification of Letters Patent. Patented May 19, 1914.

Application filed May 31, 1911. Serial No. 630,347.

To all whom it may concern:

Be it known that I, ALFRED CZARNIKOW, a subject of the German Emperor, and residing at Berlin, Germany, have invented 5 certain new and useful Improvements in Spring-Actuated Motors, of which the following is a specification.

The subject-matter of my invention is an improved spring-actuated motor or clock-work mechanism particularly for talking-machines.

The improvement consists in the particular manner in which the spring-barrel containing the spring can be loosened and re- 15 fastened, *i. e.* the improvement consists in the form and arrangement of all parts necessary for this purpose.

Detachable spring-barrels are already known but the fastening means employed 20 therefor are different from those I employ. By supporting the removable spring-barrel externally, I am able to obtain a more rigid construction and greater economy in space within the barrel than when the barrel rotates on a central pin as heretofore. Moreover I employ the spring-connected spindle 25 in the barrel as the driving agent, and by coupling this in alinement with the driven axle of the talking-machine, I reduce friction to a minimum.

The subject-matter of my invention is represented by way of example in elevation, partly in section, in the accompanying drawing.

35 1 designates the closed casing containing the gearing and the governor, 2 the spindle of the plate of the casing, 3 the winding-up axle for the spring-actuated motor, 4 the gear wheel projecting through a slot in the 40 bottom 5 of the casing and directly meshing with the bevel gear 6 of the spring-barrel 7.

The suitably projecting hub 8 of the spring-barrel 7 enters into a guide box 9 of the casing 1, while the main axle 10 of 45 the mechanism enters into the end of the correspondingly hollowed axle 11, carries pins 12 engaging in slots in this axle, and is consequently rotatably coupled with this axle. A cross-bar 15 is attached by means 50 of screws 14 on supports 13 fixed to the casing, and the box 16 on this cross-bar surrounds and guides the hub 17 of the spring-barrel and thereby guarantees the centric position of the spring-barrel relative to the 55 axle 10.

It is evident that by unscrewing the cross-bar 15 and removing the same the spring-barrel can be very simply exchanged.

I claim:—

60 In a spring-actuated motor of the character described, the combination of a casing having two pillars, a removable cross-bar screwed to the ends of the pillars, a driven-axle journaled in the casing and having an 65 end projecting therefrom between the pillars, a transverse pin fast in said end, a manually operated spring-barrel coaxial with said axle and having stub-ends journaled in the cross-bar and in the casing, and 70 a spring-driven spindle journaled concentrically in the barrel, and having at one end a pivot supported by said cross-bar and at the other end a bore and a slot respectively engaging over said end of the driven-axle 75 and over said pin.

In testimony whereof, I affix my signature in the presence of two witnesses.

ALFRED CZARNIKOW.
